Baldwin-Southwark Corporation, a corporation
of Delaware

Application March 28, 1933, Serial No. 663,198

13 Claims. (Cl. 62—103)

This invention relates generally to an air conditioning unit of the type employing a refrigerating system for cooling or heating the rooms of homes or offices, and relates more particularly to improved means for permitting accumulated condensate to be conveniently and effectively disposed of at any time when it is desired to clean the unit or prepare it for inactive use over an extended period of time, thus insuring sanitation, low maintenance cost and more efficient and satisfactory operation.

Effective cooling of room air requires reduction of humidity and this is obtained by circulating room air over an evaporator of a refrigerating system whereby moisture in the air is condensed on the evaporator surface and allowed to drip into a suitable receptacle from which the moisture is discharged to a point outside of the room. This discharge is effected preferably, but not necessarily, by conducting the collected condensate to a suitable receptacle disposed in a path of outside air which flows over the condenser for cooling the same. The condensate is entrained by this air and vaporized by the condenser heat to be effectively carried to the outside air.

When operation of the unit is stopped, a certain amount of accumulated condensate still remains and it is desirable to dispose of this in a convenient and effective manner in case the unit is to be cleaned or to be left inactive for an extended period of time thus avoiding formation of slime or other deleterious conditions.

In the specific embodiments of the invention herein shown for purposes of illustrating certain forms among others that the invention might take, the condensate collecting and disposal means are shown preferably in the form of trays and are preferably removably disposed in the unit, although if desired a fixed receptacle may be used in which case certain aspects of our invention may be employed to suitably drain the receptacle preparatory to inactive use. With removable trays it is desirable to control or drain the accumulated condensate in such a manner that the possibility of leakage or spilling of water is reduced to a minimum upon removal of the trays.

It is one object of our invention to accomplish all of the foregoing in a simple, economical and effective manner.

Another object is to provide an improved and simplified means whereby liquid in two receptacles may be conveniently and effectively disposed of at the will of the operator.

A still further object is to provide an improved

arrangement which will compel proper control of the liquid before or during removal of the trays. In one aspect of the invention, I provide a conduit, preferably flexible, adapted to be placed preferably across the front of the trays and more specifically adjacent the handles thereof so that upon grasping the same to remove the tray the conduit will offer some obstruction to removal, or at least it will serve as a reminder that it should be first disconnected before removing the tray. As specifically shown, a flexible conduit of sufficient length is intertwined through suitable openings in the trays specifically the handle openings therefor, thus more positively insuring proper operation and control of the liquid in the trays before removal thereof.

In another aspect of the invention I employ a fluid drainage control valve of such a type that it is opened automatically when a drainage conduit is associated therewith and upon disconnection of the conduit the valve is closed automatically. By providing each tray with a valve of the above type, I prevent drainage from a tray when it has been disconnected but at the same time maintain the connection open to the other tray so that water may drain therefrom through the interconnecting conduit which is preferably flexible, this flexibility permitting the liquid to be directed into any suitable pan or the like which may be placed on the floor adjacent the unit.

Other objects and advantages will be more apparent to those skilled in the art from the following description of the accompanying drawings wherein:

Fig. 1 is a perspective of an air conditioning unit positioned adjacent a window of a room in which the unit is placed, thereby permitting outside air to be circulated over the condenser for cooling the same. An end door of the unit is omitted for purposes of showing the general arrangement of parts;

Fig. 2 is an enlarged perspective of one end of the unit with one tray removed and the other tray partially withdrawn and showing the manner in which liquid may be drained from the tray, the end door of the cabinet also being removed;

Fig. 3 is a perspective of the tray removed from Fig. 2;

Fig. 4 is an enlarged end elevation of the trays showing the initial operation in draining the first tray after disconnection of the intercommunicating conduit;

Fig. 5 is an enlarged sectional view of the liquid connection employed in our combination;

Fig. 6 is another modification showing a liquid conduit arranged to be broken in such a manner that liquid may be suitably drained from each receptacle without the use of control valves, the conduit being shown in its draining position;

Fig. 7 is a modification with an intercommunicating breakable valve connection at the rear end of the trays.

In the illustrated embodiments of the invention which represents merely two forms among possible others that the invention might take, I have shown a self-contained unit generally indicated at 1 and having a vertical axis motor-compressor unit 2 adapted to compress a suitable refrigerant which is condensed in a condenser 3 and evaporated in an evaporator 4 for the purposes of cooling room air circulated thereover by a blower 5. This blower draws air from the room into one end of the cabinet and through a suitable blower inlet 6 from which the air flows upwardly through a passage 4' and over evaporator 4 disposed therein to discharge to the room through an outlet 5', formed preferably in the top of a suitable cabinet of the unit. The condenser 3 is cooled by outside air flowing inwardly through one passage portion of a window duct 7, thence downwardly over the motor-compressor unit 2 and inwardly through a suitable blower 8 to be circulated upwardly through passage 9 in which the evaporator 3 is disposed, the air thence flowing outwardly through another portion of the window duct 7. In case the unit is used for heating the room air the complementary heat exchange elements 3 and 4 may have their condenser and evaporator functions suitably interchanged thereby causing the heat exchange element 3 to serve as a condenser whereby room air will be heated in being circulated thereover. However, for purposes of description, the unit is herein considered as operating as a cooler, although it will be understood that any of the functions and mode of operation described in connection with the control or draining of the condensate would merely have to be reversed to apply the same to the heating aspects of the unit.

Removably disposed within the passage 4' is a liquid tray generally indicated at 10 which specifically is adapted to be longitudinally removed through a doorway 11 at one end of the unit, the door being omitted for purposes of clearness. This tray is disposed preferably beneath the evaporator 4 so as to collect any moisture that is condensed on the evaporator surfaces to drip downwardly therefrom. This tray may be of any suitable form for collecting the condensate and at the same time permitting upward flow of air in passage 4'. One specific embodiment of such a tray is shown in Fig. 3, wherein a series of horizontal troughs 12 are laterally spaced apart to provide passageways 13 therebetween. These troughs are connected to headers 14 and 15 suitably disposed between sides 16 and 17. An end plate 18 is provided with a suitable handle 19 while the inner end of the tray is provided with a suitable recess 20 to receive one of the two pressure reducing valves associated with each heat exchange element for purposes of permitting the functions thereof to be interchanged. As the specific manner of effecting said interchange of functions does not constitute a part of this invention, the same will not be described further. The upper edges of the sides 16 and 17 are turned inwardly as shown more particularly at 21 and 22 in Figs. 3 and 4. The tray is inserted through

a suitable opening 23 formed in an end wall of passage 4' and flanges 21 and 22 are slidably supported in suitable longitudinally extending guideways 24 projecting inwardly of passage 4' from each of the upper corners of opening 23.

Another condensate tray generally indicated at 25 is of the same construction as tray 10 except that its cross sectional overall dimensions are somewhat larger. This tray is longitudinally slidably disposed in passage 9 preferably beneath heat exchange element 3 which normally functions as a condenser when the unit operates as a room cooler.

To supply fresh outside air to the circulation of room air a suitable fresh air duct 26 projects outwardly from the end cover 18' of tray 25 and has a breakable joint connection with a suitable end chamber 27 which communicates with the inlet 6 of room air blower 5. Corresponding parts of the two trays are given the same reference numbers except that the numbers for tray 25 are primed.

To transfer condensate, which collects in collector troughs 12 and headers 14 and 15, to the tray 25 and thus permit upward flow of outside air through passages 13' to entrain the condensate and cause it to be evaporated by the heat of the condenser, I have provided an improved readily breakable and preferably, but not necessarily, flexible conduit generally indicated at 30. To connect this intercommunicating conduit to the respective headers 14 and 14' of the trays, and also, when desired, to permit each tray to be individually drained while maintaining the liquid in the other tray, I have provided valve connections 31 and 31' of the respective trays. These valves communicate with the front headers in the left and right hand corners of the respective trays thus permitting the conduit to be effectively associated with the handles 19 and 19' in a manner to be described later. In case heat exchange element 4 serves as the condenser, then the condensate which collects on element 3 will flow through conduit 30 to the tray beneath element 4 and thereafter be discharged into the room air.

Valve connections 31 and 31' are of the same specific construction and hence it will suffice to describe only one thereof such as shown in Fig. 5, wherein a valve housing 32 has a reduced portion to provide a shoulder which is welded, soldered or otherwise suitably secured to the end cover 18. A spring 33 is interposed between the inner end of casing 32 and a valve disc 34, thus normally urging the disc toward a seat element 35 herein specifically shown as rubber, although it may be of any suitable flexible or rigid seat material held in position preferably by a screw threaded plug 36. The disc 34 is slightly less in diameter than the bore 37 in which it is disposed while a suitable boss 38 encircled by spring 33 will sufficiently prevent tilting or disalignment of disc 34. A valve controlling element specifically in the form of an elbow 39 has a cylindrical portion 40 adapted to be inserted through and be frictionally held by seat material 35 to engage disc 34 and hold it away from said seat. Lateral openings 41 allow communication between the elbow passage 42 and bore 37 which in turn communicates with the tray header through opening 43. From this construction it is seen that upon removal of elbow 39, disc 34 will be pressed into engagement with seat 35 by spring 33 and thus close the seat opening to prevent any

outward flow of liquid from the header. Due to the axial length of seat material 35, disc 34 will be seated before the cylindrical portion 40 of the elbow is completely removed from the valve disc. 5 The intercommunicating conduit 30 is preferably made of rubber thus permitting the same to be readily slipped over a suitably corrugated end of elbow 39. Preferably this conduit extends from one valve 31 downwardly through handle 10 19 and thence over the face of the trays and upwardly through the handle 19' of tray 25 thus to be inserted in valve 31' although if desired this conduit may merely lie across the face of the trays, or extend over said handles or in close relation thereto. In either case, however, it is seen that the arrangement of parts offers some obstruction or hindrance to removal of one tray unless the intercommunication is disconnected. 15 In the arrangement wherein the conduit is disposed close to the handles without necessarily passing therethrough, it is seen that the handles cannot be easily grasped without also grasping the conduit, thereby reminding the person of the necessity of removing the same.

25 *Operation.*—Assuming the unit to have operated sufficiently long to accumulate condensate 45 in the trays and that it is desired to remove the same for purposes of cleaning or inspection, a suitable door in the cabinet doorway 11 first will 30 be removed and then the operative will remove the elbow 39' from valve 31' as shown in Fig. 4. Upon removal of elbow 39', the valve disc therefor is automatically seated to prevent discharge 35 of water from tray 25 but at the same time the valve disc for valve 31 is maintained unseated by nipple 40, thus permitting water from tray 10 to drain through elbow 39 to any suitable receptacle 40 46 that might be placed upon the floor. When tray 10 has been completely drained, it may be removed as shown in Fig. 3. Nipple 39 will then 45 be removed from its tray and nipple 39' inserted in valve 31' to thereupon drain tray 25. Upon insertion of nipple 39', the valve disc of valve 31' is unseated, thereby permitting water to be 50 drained through nipple 39 into the receptacle 46 as shown in Fig. 2. When tray 25 is completely drained, it may be removed without danger of spilling water on the floor or without liability of water draining into the unit.

55 In the modification of Fig. 6 a preferably, but not necessarily, flexible conduit 50 is suitably connected to trays 10' and 25', the conduit having at all times constant communication with the trays without any valves being used. To compensate for this omission of valves and yet permit control and convenient disposal of the liquid in the trays, there is provided a suitable breakable joint 51 disposed preferably midway of the ends of the conduit. This joint may be of simple 60 form such as a pipe nipple slipped into the ends of the conduit to connect the same, the conduit preferably being of rubber although metal pipe sections may be used with a swivel joint connecting each pipe section with the trays in which case a rubber nipple may be used to connect the adjacent ends of the pipe sections. Usual forms of garden hose snap connections may also be used if desired. However, with any form of conduit or breakable joint it is seen that upon breaking 65 the joint the two approximately equal length or separated conduit sections may be turned downward to drain simultaneously the liquid from the trays into a suitable receptacle on the floor. The conduit may be arranged with respect to the trays

and handles thereof in any of the manners used for the valved conduit.

In Fig. 7 there is diagrammatically shown a conduit 55 permanently secured to the unit frame in any suitable manner and having elbows 56 and 57 projecting forwardly to be slidably received in valves 58 and 58' which are identical to valves 31 and 31'. These valves are carried by the trays similar to the preferred arrangement except of being at the rear of the trays. The trays are of 10 the same construction as in Fig. 3 and when in normal position both valves are opened by the conduit elbows holding the valve discs off their seats, thus allowing communication between the trays. To drain the trays it is only necessary to 15 first pull out slightly and simultaneously both trays thus causing both valves to close. The trays, one at a time, may then be completely removed with water therein and the water poured therefrom. The trays may then be reinserted 20 into the unit thereby to open the valves and allow communication between the trays.

From the foregoing disclosures it is seen that I have provided an extremely simple arrangement whereby the condensate accumulated in 25 the unit may be conveniently and effectively drained or disposed of in a simple manner with arrangements having a low cost and which co-operate with removable trays to permit freedom 30 and full functioning of the removable features, this being accomplished with minimum possibility of spilling water or allowing leakage there- 35 of.

It will of course be understood by those skilled in the art that various changes may be made 40 in details of construction and arrangement of parts without departing from the spirit of the invention as set forth in the appended claims.

We claim:

1. Air conditioning apparatus comprising, in 45 combination, a pair of condensate receptacles, a conduit adapted to allow communication between said receptacles, and means provided for breaking said conduit to allow each of said receptacles to drain.

2. Air conditioning apparatus comprising, in combination, a pair of condensate receptacles, a conduit connected to said receptacles to allow communication therebetween, and a breakable joint at an intermediate portion of said conduit 50 whereby upon breaking of said joint the liquid in both of said receptacles may be drained and directed through the separated portions of the conduit.

3. Air conditioning apparatus comprising, in 55 combination, a pair of condensate receptacles, a conduit connected to said receptacles to allow constant communication therebetween, and a breakable joint at an intermediate portion of said conduit whereby upon breaking of said joint 60 the liquid in both of said receptacles may be simultaneously drained and directed through the separated portions of the conduit.

4. Air conditioning apparatus comprising, in 65 combination, a pair of trays removable from said apparatus, an intercommunicating conduit therebetween, and means whereby said trays may be first drained before removal thereof.

5. Air conditioning apparatus comprising, in 70 combination, a pair of trays removable from said apparatus, means for draining said trays, and means including said drainage means to restrict removal of said trays.

6. Air conditioning apparatus comprising, in 75 combination, a pair of condensate trays remov-

- able from said apparatus and having openings therein, and a conduit to allow communication between said trays and adapted to be passed through said openings to restrict removal of said trays.
7. Air conditioning apparatus comprising, in combination, a pair of condensate receptacles, an intercommunicating conduit therebetween, and means whereby said conduit is adapted to drain one of said receptacles while the other is prevented from being drained.
8. Air conditioning apparatus comprising, in combination, a pair of condensate receptacles, an intercommunicating conduit therebetween, and means whereby said conduit is adapted to drain one of said receptacles while the other is prevented from being drained and vice versa.
9. Air conditioning apparatus comprising, in combination, a pair of condensate receptacles, a valve controlled outlet in each of said receptacles, a conduit adapted to be removably associated with each of said valve outlets to permit communication therebetween, said valve outlets having provision to be closed automatically upon removal of the conduit therefrom while the other valve outlet remains open.
10. Air conditioning apparatus comprising, in combination, a pair of condensate trays, a conduit extending across the ends thereof and allow-
- ing communication therebetween, and valve controlled outlets between said conduit and each of said trays whereby upon disconnection of said conduit from either of said valve outlets said trays may be drained and removed.
11. Air conditioning apparatus comprising, in combination, a pair of removable condensate trays, a valve outlet associated with each of said trays, each of said valves having a relatively long opening closed by a spring-held valve disc, and a conduit adapted to allow communication between said trays and to open said valve disc by being insertable within said valve openings and engaging the discs to move the same away from their valve seats.
12. Air conditioning apparatus comprising, in combination, a pair of condensate receptacles, and means forming a conduit adapted to allow fluid flow in either direction between said receptacles, said means having provision for draining said receptacles.
13. Air conditioning apparatus comprising, in combination, a pair of condensate receptacles, and means forming a conduit adapted to allow fluid flow in either direction between said receptacles, said conduit including a flexible portion.

CHARLES R. NEESON.
ARTHUR S. LOCKE.
